MULTIPURPOSE RHYTHM DEVICE

Everett H. W. Clayton, Long Island City, N. Y.

Application June 28, 1950, Serial No. 170,860

10 Claims. (Cl. 84—170)

The present invention relates to drummer's traps and equipment and has over-all relation to a combination rhythm sounding device. More particularly, I have evolved and produced a novelly unique contrivance having coordinated simultaneously actuatable facilities enabling a user to beat out rhythms thereon as an entity, or in combination with other instruments in a manner to set the pace and rhythmical time for dancers doing rhumbas, sambas, polkas, calypsos, and so on and so forth.

Novelty is predicated on a multi-purpose construction which lends itself as an accompaniment instrument for dance bands, orchestras, for small group combinations, and which may be played by itself to mark timed beats for dances of all types.

One aspect of the invention has to do with a simple and practical precision-type structure which is characterized by a horizontal base, a "washboard" attached to and rising vertically from said base, vertically reciprocable means including a head having fingers to be raked against adjacent corrugations of the stated "washboard," and a simple foot pedal on the base operatively connected with and for actuating said means.

Another object of the invention is to provide a base, a standard attached to and rising vertically from the base, a horizontally disposed bow-spring attached to the upper end of the standard and provided on each end with a marracas, a hinged foot pedal on the base and an operating connection between the pedal and spring, whereby to rhythmically flex the bow-spring, and in so doing to agitately shake the two marracas coincident with the rhythm pattern to be executed.

A still further object of the invention is to provide a time beating rhythm contrivance which is characterized by the stated base and standard on the base, there being a spring-return sleeve slidable on said standard and said sleeve being operated up and down by the hinged foot pedal, said sleeve being further novel in that it is provided with a cross-head to operate, through the medium of push-pull rods, a pair of wooden or equivalent afterbeat clappers hingedly mounted on the standard.

Other objects and advantages will become more readily apparent from the following description and the accompanying illustrative drawing.

In the accompanying sheet of drawings, wherein like numerals are employed to designate like parts throughout the views:

Figure 1 is a perspective view of a multi-pur- 65 ure 2, they are "down."

pose rhythm beating contrivance constructed in accordance with the principles of the present invention.

Figure 2 is a view in elevation, the view being fragmentary in type, and showing the down positions of the marracas and the open positions of the clappers.

Figure 3 is a fragmentary view with parts in section and elevation taken on the horizontal line 3—3 of Figure 1, looking in the direction of the arrows.

Figure 4 is an enlarged fragmentary sectional view on the vertical line 4—4 of Figure 1, looking in the direction of the arrows.

15 Referring now to the drawings by reference numerals and lead lines, the horizontal base, which may be substantially triangular in top plan view, is denoted by the numeral 6. A complementary board 8 is superimposed upon the left-hand 20 end of the board 6, and interposed between this and the base is a metal strip 10 fastened in place at 12. The headed lower end 14 of a vertical standard 16 is fitted into a recess 18 in the base and the screw-threaded portion 20 extends 25 through the metal strip by way of a suitable opening and through an additional opening in the board 8. An assembling and clamping nut 22 serves to fasten the parts together and to mount the standard centrally on the base. A sleeve 24 is slidable on the standard and a coiled spring 26 surrounds the standard and bears at one end against the base and at its opposite end against a collar 28 carried by the lower end of the sleeve. The numeral 30 designates a suitable foot pedal which is hinged on the base, as at 32. The pedal is provided with a hook 34 joined with a link 36 which, in turn, is operatively connected with the collar 28. Thus, the pedal is depressed to move the sleeve down against the tension of the spring 26 and the spring serves to return both the sleeve and pedal to their normal "up" positions. There is a cross-head at 38 made up of a pair of complementary strip members 40 and 42 and these are suitably fastened in place as at 44. The sleeve is provided with a stop flange 46, as shown in Figure 4. A resiliently flexible bow-spring 48 having upturned ends is secured at its intermediate portion, as at 50, on the upper end of the standard. A marracas 52 or an equivalent rhythm device is mounted on the bow-spring. These two instrumentalities 52 are adapted to be swung up and down to produce the desired shaking strokes. In Figure 1, they are "up" and in Figure 2, they are "down."

2

Coiled springs 54—54 are operatively connected at their lower ends to the outer end portions of the cross-head 38 and have their upper end portions 56—56 connected with the outer end portions of the bow-spring 48 for purposes of flexing the latter in an obvious manner.

At this time attention is directed to the complementary pair of clappers 58 and 60. These may be suitably shaped boards. The main clapper 58, as shown in Figure 4, is hinged on an axle 62 which is carried by the standard and provided with a spacing sleeve 64, a coiled spring 66 and a wing nut 68. As shown in Figure 2, the smaller clapper board 60 is hingedly mounted at 70 on the clapper board 58. Suitably bent push-pull rods 72—72 are secured respectively at their upper ends to the clappers 58 and 60 and operatively connected at their lower ends to the outer end portion of the cross-head 38. These clappers are employed to produce, obviously, an after-beat. They are opened and closed by the pedal action and the sliding of the sleeve on the standard plus the push-pull rod 72.

At this time, attention is directed to the primary rhythm beating unit and this is denoted by the numeral 74. This type of device has come to be known in the profession as a "washboard." Actually, however, it here comprises a pair of uprights 76—76 which are attached to and rise vertically from one end portion of the base. These uprights are suitably grooved, and the grooves serve to accommodate a corrugated plate or diaphragm 78. The beats are produced on the diaphragm by a unique rake-like head 80. The head comprises a plurality of spaced parallel horizontal rounds 82 having secured therebetween right angularly disposed cylindrical blocks 84. The blocks are vibrating fingers and have slideable or wiping contact with the corrugations on the diaphragm. A suitably shaped, depending resilient arm 86 is provided and this is secured at its lower end as shown in Figure 3 to the head 80. The upper end of the rod is attached by a collar 88 fastened on and movable with the sleeve 24.

The unitary results obtainable in this over-all combination of companion instrumentalities is produced by a simple hinged pedal on a single base. Therefore, as the pedal is depressed and released in customary drummer-like fashion, the one movement serves to simultaneously operate the various coordinated rhythm-making devices. That is to say, the raker head 80 sweeps up and down against the corrugations to produce a primary rhythm pattern. At the same time, the downward movement of the pedal causes the downwardly sliding sleeve to straighten out the bow-spring and to set each marraccas 52 into motion. The up-and-down movement of the parts 52 permits the same to produce the desired rhumba effect. The cross-head on the sleeve also operates, as stated, the clappers and these produce the after-beat.

It will be obvious from the disclosure that novelty is believed to be present in the main sub-combinations as well as in the over-all combination, in that a single base with a single pedal and single upright coordinate the several devices to produce the desired individual sounds in proper progressive relationship.

If desired, the aforementioned bracing strap or strip 10 may be provided, at one end, with a head plate 11 and the latter may be used to ornament and "dress up" the base 6. That is to say, head plate 11 may be a name plate and thus carry suitable emblems or other insignia.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. A rhythmical sound-producing percussive contrivance for use by drummers and others comprising a horizontal base, a vibratory diaphragm having horizontal corrugations and secured to and rising vertically from said base, a vertically reciprocable head having rigid raker fingers in wiping contact with the corrugations of said diaphragm, a foot pedal pivoted for operation on said base, and an operating connection between said pedal and head.

2. A percussion instrument for use by drummers and others comprising a horizontal base, a horizontally corrugated diaphragm secured to and rising vertically from said base, a vertical standard fixed on said base in close spaced parallelism with said diaphragm, means slidably mounted on said standard having elements contacting and adapted to be raked up and down across the corrugations on said diaphragm, a foot pedal pivotally mounted on said base, and an operating connection between said pedal and means.

3. The structure defined in claim 2, wherein said means embodies a sleeve reciprocable on said standard, a coiled spring surrounding the standard with one end resting on the base and the other end engaging the sleeve, an arm carried by said sleeve, and a rake-like head carried by said arm.

4. The structure defined in claim 3, wherein said head comprises a plurality of spaced horizontal rounds and cylindrical blocks secured between the rods, said blocks constituting raking fingers and having vibratory wiping contact with the corrugations of said diaphragm.

5. A rhythmical time beating contrivance usable as a drummer's trap comprising a base, a vertical standard attached to and rising from said base, a bow-spring secured midway between its ends to the upper end of said standard, a marraccas mounted on each end of said spring, a foot pedal hinged for operation on said base, and an operating connection between said pedal and the opposite end portions of said bow-spring.

6. The structure defined in claim 5, wherein said operating connection embodies a sleeve slideable on said standard, a cross-head carried by said sleeve, and flexible connections between the ends of the cross-head and ends of said bow-spring.

7. The structure defined in claim 6, and a pair of after-beat clappers swingably mounted on said standard, and push-pull rods secured to the opposite end portions of said cross-head and the respective clappers.

8. A rhythmical time beating contrivance usable as a drummer's trap comprising a base, a vertical standard attached to and rising from said base, a spring-returned sleeve slideable on said standard, a cross-head carried by said sleeve, a pedal hinged on said base and operatively con-

nected with said sleeve to slide latter up and down, a pair of after-beat clapper boards hingedly mounted on said standard, and a pair of push-pull rods secured respectively to the clapper boards and cross-head.

9. A rhythm device of the class shown and described comprising a base, a vertically disposed corrugated plate attached to and rising from one end of the base, a standard attached to and rising vertically from the base and disposed in parallelism with said corrugated diaphragm, a sleeve vertically reciprocable on said standard, a coiled spring surrounding the standard and interposed between the base and one end of the sleeve, a foot pedal hingedly mounted on the base and operatively connected with said sleeve for moving the latter up and down, a resilient arm fastened to and depending said sleeve and interposed between the sleeve and corrugated diaphragm, a head structure mounted on the lower end of said arm and shiftable up and down in relation to the diaphragm and provided with fingers in raking contact with the corrugations of the diaphragm, a bow-spring mounted on the upper end of said standard, rhythm-producing shaker devices attached to the respective outer ends of said bow-spring, a cross-head secured to the upper end of said sleeve, operating connections between the end portions respectively of the cross-head and bow-spring.

10. A rhythm device of the class shown and described comprising a base, a vertically disposed corrugated plate attached to and rising from one end of the base, a standard attached to and rising vertically from the base and disposed in parallelism with said corrugated diaphragm, a

sleeve vertically reciprocable on said standard, a coiled spring surrounding the standard and interposed between the base and one end of the sleeve, a foot pedal hingedly mounted on the base and operatively connected with said sleeve for moving the latter up and down, a resilient arm fastened to and depending said sleeve and interposed between the sleeve and corrugated diaphragm, a head structure mounted on the lower end of said arm and shiftable up and down in relation to the diaphragm and provided with fingers in raking contact with the corrugations of the diaphragm, a bow-spring mounted on the upper end of said standard, rhythm-producing shaker devices attached to the respective outer ends of said bow-spring, a cross-head secured to the upper end of said sleeve, operating connections between the end portions respectively of the cross-head and bow-spring, a pair of opposed clappers, one clapper hingedly mounted on said standard and the other clapper hingedly mounted on the first-named clapper, and push-pull rods secured at their upper ends to the respective clappers and at their lower ends to the 25 outer end portions of said cross-head.
